LAUNDRY RECEPTACLE

Filed April 14, 1927

UNITED STATES PATENT OFFICE

SAMUEL KATZMAN, OF BROOKLYN, NEW YORK

LAUNDRY RECEPTACLE

Application filed April 14, 1927. Serial No. 183,642.

My invention relates to laundry receptacles, commonly known as clothes hampers, for the collection of laundry, which is deposited therein piecemeal from time to time and entirely removed therefrom periodical-
ly for the purpose of being laundered.

An object of my invention is the provision of a neat-looking and sanitary laundry receptacle, having a separate opening which is readily accessible for the insertion therethrough of soiled laundry, and having another separate opening to which easy access may be had for the removal therethrough of the collected laundry for the purpose of being laundered.

Another object is the provision of a laundry receptacle for use in private homes, hotels and the like, which is adapted to be built into a wall of a basement, bathroom, hall or any other desirable and convenient location for the collection of soiled laundry. This built-in type of laundry receptacle saves valuable space, is completely out of the way, and gives a cleaner and neater appearance to whatever place it may be built into.

One feature of my invention is the provision of a separate compartment in the laundry receptacle for collecting small articles, such as handkerchiefs, collars, stockings, etc., thereby keeping same apart from the larger articles, such as shirts, underwear, bedsheets, etc. With this feature there is obviated the necessity of sorting the laundry at the time it is removed from the receptacle and delivered to the laundryman to be laundered, with a consequent saving of time and trouble.

Other objects and features of the invention will appear from the following description of an embodiment of the invention shown merely for the purpose of affording an understanding of the invention, and not for imposing limitations thereon. In the accompanying drawings forming a part hereof, Fig. 1 is a perspective view of the built-in type of laundry receptacle, showing same

built into a wall. Fig. 2 is a perspective view with parts broken away of a laundry receptacle similar to that of Fig. 1, having a drawer therein for the collection of small articles. Fig. 3 is a cross-sectional view taken on the line 3-3, Fig. 2. Fig. 4 is a perspective view of a laundry receptacle of the unattached type, which may be placed wherever desired and its location changed at will.

Referring first to the built-in type of laundry receptacle illustrated in Figs. 1, 2 and 3, the device comprises a container, preferably of oblong form, having a flat front wall 10, a flat top 12, flat sides 14, a flat back wall 16, and a flat bottom wall 18. In order that this type of receptacle may be built-in or recessed into a room wall, the front wall 10 of the container is provided on all of its sides with a straight, outwardly extending flange 20, which flange 20, when the receptacle is installed, is flush with the outer surface of the room wall 22 into which the receptacle is built.

Laundry desired to be collected in the receptacle is deposited through an opening 24 arranged preferably transversely of the front wall 10 and in the upper portion thereof. Said opening 24 is normally kept closed by a door 26, preferably opening outwardly and hinged on its lower edge to the front wall 10. For the removal from the receptacle of the collected laundry, an opening 28 is provided in the lower portion of the front wall 10, said opening 28 being preferably larger than the depositing or receiving opening 24. Opening 28 is normally kept closed by a door 30, preferably opening outwardly and hinged on one of its sides to the front wall 10 of the container. Doors 26 and 30 are preferably provided with suitable catches 32 to hold said doors shut.

In the modified form of built-in laundry receptacle shown in Figs. 2 and 3, I preferably provide a small compartment within

said receptacle for collecting small articles, such as collars, stockings, handkerchiefs, etc., in order to keep same separate from the larger articles deposited in the receptacle 5 through the depositing door 26. Said compartment preferably comprises a drawer 34 provided on two of its sides with tracks 36, which are adapted to slide in and out on slideways provided on the interior of the 10 side walls of the receptacle (not shown). In order that larger articles deposited through door 26 may fall into the bottom of the receptacle and not be caught on drawer 34 or be hindered thereby, I preferably provide 15 vide a downwardly curved baffle 38 attached to the interior of the front wall 10 above the drawer 34. If articles deposited through door 26 should fall on baffle 38, they do not remain there but slide off and fall into the 20 bottom of the laundry receptacle and are removed therefrom through door 30. Although in the drawings, the drawer 34 is shown positioned between depositing door 26 and removal door 30, said drawer may be placed 25 elsewhere on the container where easy access thereto may be had.

The unattached type of laundry receptacle shown in Fig. 4 is similar to the built-in receptacle shown in Fig. 1, except that the 30 depositing door 26', instead of being in the upper portion of front wall 10', is located in the top wall 12', and opens upwardly. If desired, this unattached type of laundry receptacle may also be provided with the drawer 35 for small articles, as shown in Figs. 2 and 3.

In order to ventilate the interior of my improved receptacle, I preferably provide one of its walls with a foraminated panel or with a number of foramina 40 in one or 40 more of its walls. Although in the drawings I have shown the front walls of the receptacle so foraminated, it is understood that said foramina may be provided in other places on the receptacle.

45 If desired, the inner walls of the receptacle may be provided with hooks and a laundry bag of canvas, or any other suitable material, attached in open position within the receptacle on said hooks, so that when 50 soiled laundry is deposited in said receptacle it will fall into and be collected in said bag, and when it is desired to empty the laundry receptacle for the purpose of laundering the articles collected therein, instead of removing 55 the articles piecemeal, the entire contents of the receptacle may be conveniently removed at one time by simply detaching and removing from the receptacle the bag containing the collected laundry.

60 The laundry receptacle of the present invention may be made in any shape or size, and may be constructed of sheet metal, wood, fibre or any other suitable material.

65 It will be obvious from the foregoing that the laundry receptacle of my invention has

a neat and pleasing appearance, is very sanitary, constitutes a great convenience wherever used, and enables a saving of time and trouble, which the busy housekeeper can particularly appreciate.

70 Changes and modifications may be resorted to within the scope of my claims without departing from the spirit of my invention.

I claim:

1. A laundry receptacle comprising a flat-sided container having an opening in the upper portion of its front wall for the deposit into said receptacle of large articles of laundry to be collected, a second opening in the lower portion of its front wall for the removal from said receptacle of said collected laundry, a drawer between said two openings for the deposit therein of small articles of laundry to be collected, and a baffle secured within the receptacle and extending from a point substantially above the forward end of said drawer thence rearwardly and downwardly to a point above the rear end of the drawer, said container from said upper opening past said baffle to said lower opening forming a continuously open passage of sufficient capacity to permit of the articles deposited into the receptacle through the upper opening falling to the bottom of the receptacle to be removed through the lower opening, and doors for controlling said openings mounted to be disposed in both the opened and closed positions thereof out of the path of travel through said passage.

2. A laundry receptacle comprising a substantially upright container having an opening in the upper portion of its front wall for the deposit into said receptacle of large articles of laundry to be collected, a second larger opening in the lower portion of its front wall for the removal from said receptacle of said collected laundry, a drawer in said receptacle between said two openings for the deposit therein of small articles of laundry to be collected, and a downwardly curved baffle secured within the receptacle and extending from a point substantially above the forward end of said drawer thence rearwardly and downwardly to a point above the rear end of the drawer, said container from said upper opening past said baffle to said lower opening forming a continuously open passage of sufficient capacity to permit of the large articles deposited into the receptacle through the upper opening falling to the bottom of the receptacle, doors for controlling said openings mounted to be disposed in both the opened and closed positions thereof out of the path of travel through said passage, and means disposed between said doors for ventilating the interior of said container.

3. A laundry receiving device comprising a substantially upright, elongated container having an elevated opening in the upper por-

tion of the front wall thereof through which the laundry is received, and an opening in the lower portion thereof through which the accumulated laundry is removed, said container from the upper opening to the lower opening forming a continuously open substantially vertical passage of sufficient capacity to permit of the soiled articles inserted dropping to the bottom thereof to accumulate therein, a flange portion about the periphery of said front wall projecting laterally beyond the outlined of said container, the latter being receivable within an opening in a wall with the flange portion thereof engaging said wall, and closures for said openings mounted to be disposed in both the opened and closed positions thereof out of the path of travel through said passage, and in the closed positions thereof lying substantially in the plane of said front wall and said flange portion.

4. A laundry receiving device comprising a substantially upright, vertical container having an elevated opening in the upper portion of the front wall thereof of ample area to receive the pieces of laundry into the container, and a larger opening in the lower portion of said front wall through which the accumulated laundry is removed, said container forming a substantially continuously open passage from the upper opening to the lower opening of sufficient capacity to permit of the soiled articles inserted dropping to the bottom to accumulate therein, a flange portion about the periphery of said front wall projecting laterally beyond the outlines of said container, the latter being receivable within an opening in a wall with the flange portion thereof engaging said wall, doors for said openings hinged for outward movement and disposed in the closed positions thereof substantially in the plane of said front wall and said flange portion, and means opening through the front of the container for ventilating the interior thereof.

5. A laundry receiving device comprising a substantially upright, elongated container having an elevated opening in the upper portion of the front wall thereof of ample area to receive the larger pieces of laundry into the container, and an opening in the lower portion of said front wall through which the accumulated laundry is removed, a drawer disposed within the confines of said container in offset relation to said openings for receiving smaller pieces of laundry, said container forming a substantially continuously open passage from the upper opening to the lower opening of sufficient capacity to permit of the soiled articles inserted dropping to the bottom to accumulate therein, a flange portion about the periphery of said front wall projecting laterally beyond the confines of said container, the latter being receivable within an opening in a wall with the flange portion

thereof engaging said wall, hinged doors for said openings disposed in all positions thereof outside of the path of travel through said passage and in the closed positions thereof substantially in the plane of said front wall, the front of said drawer, and said flange portion, and open means through the front of the container for ventilating the interior thereof.

In testimony whereof, I have signed my name hereto.

SAMUEL KATZMAN.
